BUNION CORRECTOR

Jeremiah C. Day and William F. Marshall,
Lexington, Ky.

Application November 21, 1938, Serial No. 241,684

1 Claim. (Cl. 128—81)

This invention relates to improvements in devices for the correction of foot deformities and its general object is to provide a device of that character commonly called a bunion corrector, in that it is especially designed for correcting deformities of the first metatarsal joint.

Another object of the invention is to provide a bunion corrector that can be worn at all times, and functions to exert a gentle pulling action 10 on the great toe, acts as an anterior support for the first metatarsal joint, prevents pronation and abduction thereof, as well as reduces both friction and pressure thereon, so as to cooperate with the pulling action to cause the joint and toe to assume their normal positions, therefore 15 it will be obvious that our device, corrects, remedies and prevents one of the most painful deformities of the foot, namely the enlargement of the first metatarsophalangeal articulation, commonly called a bunion.

A further object is to provide a bunion corrector constructed to provide pad receiving pockets wherein soft pliable material such as cloth, felt, cotton or lamb's wool may be removably placed in suitable quantities to vary the thickness of the padded areas of the device in accordance with the existing condition of the deformity and the desires of the wearer.

An extremely important object is to provide 30 a bunion corrector that is interchangeable, that is, it can be used with equal efficiency on either the left or right foot without any structural changes in the device whatsoever.

A still further object is to provide a bunion corrector that is simple in construction, inexpensive to manufacture and extremely efficient 35 in use and service.

This invention also consists in certain other 40 features of construction and in the combination and arrangement of the several parts, to be hereinafter fully described, illustrated in the accompanying drawing and specifically pointed out in the appended claim.

In describing the invention in detail, reference 45 will be had to the accompanying drawing wherein like characters denote like or corresponding parts throughout the several views, and in which:

Figure 1 is a top plan view illustrating one 50 form of our device applied to a foot.

Figure 2 is a perspective view of the device 55 as shown in Figure 1.

Figure 3 is a sectional view taken approximately on line 3—3 of Figure 2, looking in the direction of the arrows.

Figure 4 is a perspective view of a slightly modified form of the device.

Referring to the drawing in detail, and particularly to the form as shown in Figures 1 to 3 inclusive, the reference numeral 1 broadly indicates the body of our device and which is formed from a pair of layers of relatively thin pliable sheet material such as felt, leather or any material suitable for the purpose, shaped and stitched together about the major portion of its marginal 10 edges to provide a substantially oval shaped enlarged portion 2 merging into a substantially rectangular extension 3 having an open outer end 5 to provide a mouth 4 for a pocket.

In this form, both of the layers of material are 15 cut away to provide a substantially oval shaped opening 6, extending along the longitudinal center of the body for disposal partially within the enlarged portion and the extension, as best shown in Figure 2, for receiving the bunion, and the layers about the edges of the openings 6 are likewise stitched together, as best shown in Figure 3. One of the layers adjacent to the rear end of the body is slit transversely as at 7 to provide a mouth for a pocket 8 between the layers 25 of the enlarged portion, and this pocket as well as the pocket 5 is adapted to receive any suitable soft pliable padding material 9, and while lamb's wool is preferred, we may use cloth, felt or cotton, but it will be obvious that any quantity of 30 padding material may be inserted in the pockets to vary the thickness thereof in accordance with the desires of the wearer.

Secured to the enlarged portion 2 upon diametrically opposite sides thereof are the ends 35 of a foot encircling band 10 which is made from any suitable elastic material, such as webbing or the like, for securing the body laterally of the foot to bear against that portion thereof about the first metatarsal joint and with the opening 40 about the latter, and so that the extension 3 is engaged with the great toe upon the outer side thereof, as best shown in Figure 1.

The extension has secured thereto upon diametrically opposite sides thereof at its outer 45 end, the ends of a toe encircling band 11 which is likewise made from any suitable elastic material and has secured thereto for disposal in a plane parallel to the extension a pocket member 50 12 which is made up of a pair of layers of material such as felt, leather or the like shaped to provide straight upper and lower edges and a rounded forward edge, while the rear edge is straight. The layers of the pocket member 12 are stitched about the upper, lower and rounded 55

forward edge, but the straight rear edge is left open to provide a mouth 13 for the passage of padding material 14 such as lamb's wool or the like within the pocket member, as will be apparent upon inspection of Figure 3.

The pocket member is disposed between the great toe and the toe adjacent thereto as clearly shown in Figure 1.

From the above description and disclosure of the drawing, it is believed that it will be obvious that when our device is applied to the foot, as shown in Figure 1, that the body acts as an anterior support for the first metatarsal joint and cooperates with the pulling action of the pocket member 12 against the inner side of the great toe to cause the latter and the joint to assume their normal positions, and thereby correct the condition that brings about the enlargement or bunion at the first metatarsal joint.

The form of Figure 4 is a substantially similar to that of the other form in that it includes a body provided with a substantially oval shaped enlarged portion 15 and an extension 16, but in this form, only one of the layers of the material from which the body is made has an opening 17 therein for receiving the bunion, and the toe encircling band 18 is integral with the layers of material that make up the body, as well as with the pocket member 19. In that respect, it will be noted that each of the layers are shaped to provide a portion of the toe encircling band and formed on those portions are enlarged outer ends sewed together to provide the pocket member 19. The extension 16 in this form projects at a slight angle from the oval shaped portion. The foot encircling band 20 of this form is secured to the elongated portion 15, at its juncture thereof with the extension 16, and of course it will be understood that the band 20 is made from any suitable elastic material, such as webbing or the like.

While the form of Figures 1 to 3 is shown as being applied to the left foot in the drawing, it is interchangeable or can be used with equal efficiency on either foot, without any change whatsoever in the device, due to the symmetrical shape of the body as shown, and the fact that the bunion receiving opening extends entirely through the body. The interchangeable feature

is of utmost importance, as it eliminates the necessity of making the device for each foot, as well as the dealer stocking a larger quantity of the devices to meet the requirements of all sizes for both feet.

The device of the form of Figure 4 is not interchangeable, but it is otherwise capable of performing all the functions of the form of Figures 1 to 3.

It is thought from the foregoing description that the advantages and novel features of the invention will be readily apparent.

It is to be understood that changes may be made in the construction and in the combination and arrangement of the several parts, provided that such changes fall within the scope of the appended claim.

What we claim is:

A bunion corrector comprising a body made up of a pair of layers of pliable sheet material stitched together about the edges thereof to provide a body including a relatively large substantially oval shaped portion and a relatively narrow extension projecting forwardly from the oval shaped portion for disposal against the outer side of the great toe, a foot encircling band of elastic material attached to the oval shaped portion for securing the body against the first metatarsal joint to provide an anterior support therefor, said body having a bunion receiving opening therein and said layers being stitched together about the opening, said extension having an open forward end providing a mouth for a pocket between said opening and said open end, one of said layers being slit within the area of the oval shaped portion to provide a mouth for a pocket within the oval shaped portion, padding receivable in the pockets in any predetermined quantity to adjust the thickness of the padded areas of the body, a band secured to the outer end of the extension to encircle the great toe, toe engaging means secured to the latter band for disposal between the great toe and the toe next thereto and being in the form of a pocket having an open rear end providing a mouth therefor, and padding within the latter pocket.
